UNITED STATES PATENT AND TRADEMARK OFFICE

Certificate

Patent No. D-257,149

Patented September 30, 1980

Carl C. Jacobson

Application having been made by Carl C. Jacobson, the inventor named in the patent above identified, and Grafco, Inc., the assignee, for the issuance of a certificate under the provisions of Title 35, Section 256, of the United States Code, adding the names of Mark C. Manning and Francis K. Hill as joint inventors, and a showing and proof of facts satisfying the requirements of the said section having been submitted, it is this 19th day of Feb., 1985, certified that the names of the said Mark C. Manning and Francis K. Hill are hereby added to the said patent as joint inventors with the said Carl C. Jacobson.

Fred W. Sherling,
Associate Solicitor.
